[57] CLAIM

The ornamental design for a cap that transforms into a beret or visor, as shown and described.

DESCRIPTION

FIG. 1 is a front elevational view of a cap that transforms into a beret or visor showing our new design, the bottom is not part of the claimed design;

FIG. 2 is a front elevational view of the cap that transforms into beret or visor, the visor is shown separately for purposes of illustration; and,

FIG. 3 is a rear elevational view of the cap that transforms into beret or visor, the beret is shown separately for purposes of illustration.
